H. SOLOMON,
TIE FORMER AND HOLDER.
FILED OCT. 24, 1921.

UNITED STATES PATENT OFFICE.

HARRY SOLOMON, OF ST. JOSEPH, MISSOURI.

TIE FORMER AND HOLDER.

Application filed October 24, 1921. Serial No. 509,839.

To all whom it may concern:

Be it known that I, HARRY SOLOMON, a citizen of the United States, and resident of St. Joseph, county of Buchanan, State 5 of Missouri, have invented a certain new and useful Improvement in Tie Formers and Holders, of which the following is a complete specification:

This invention relates to tie forming devices for collars, and has for its object to provide a device whereon a four-in-hand tie can be tied and retained indefinitely, and which can be readily and efficiently secured to or disengaged from a collar when around 10 the neck of a wearer.

Another object is to provide an attachment which covers and completely hides the buttoned ends of the collar and hence improves the appearance of both collar and 15 tie.

A still further object is to produce an attachment made up of one or two parts, which is of simple, durable and cheap construction, and which,—in its preferred 20 form,—if of the same color as the collar, will be visible but so inconspicuous as not to be noticeable to an observer.

I am aware that made-up ties of different types have been marketed, provided with 25 metal or equivalent devices for detachable engagement with the front collar button, and others in which the ties have attached bands for encircling the collar and detachably engaging at their free ends with the 30 ties to clamp and secure them in place. My invention as contrasted with such ties, has the advantage of permitting the wearer to express individuality in the character of the knot tied to vary the style thereof at will, 35 and in addition to so adjust the tie as to present different portions thereof at the exposed part of the knot to maintain the freshness or newness thereof and to increase 40 its period of service.

Before proceeding with a detailed description of the invention in the several forms here presented, it is desired to state that it is susceptible of practical use only in conjunction with collars of the turned-down 45 or folded type, as the turned-down outer portions of such collars are relied upon to cover the ends of the attachment and assist in holding it in proper position.

Figure 1 is a front view of a device embodying the invention, applied to a collar and with a four-in-hand tie in place;

Figure 2 is a top plan view thereof;

Figure 3 is a detail of part of the device;

Figure 4 is a detail of another part of the device;

60

Figure 5 is a modified form of the part shown by Figure 4;

Figure 6 is a view of a modification of the part shown by Figure 3;

65

Figure 7 is a view of a part corresponding to Figure 4, but of proportion to engage the part shown by Figure 6;

Figure 8 is a perspective view of the part shown by Figure 3, with a clip for engagement with a collar button;

70

Figure 9 is a front view of another modification on the device;

Figure 10 is a perspective view of the hinged element of Figure 9;

75

Figure 11 is a front view of the device adapted for use upon a soft collar; and

Figure 12 is a front view of another form of the device.

In the drawing, 1 indicates a turned-down collar of the starched or stiff type, 80 adapted to fasten at the front by buttoning its ends to the front collar button (not shown) of the shirt.

In the preferred form of the attachment, there is a stiff member 2, having a hole 3 85 to engage the collar button and cover the overlapping buttoned tabs or ends of the collar, and to fit at its ends against the collar band beneath the turned-down portion of the collar, as indicated in Figure 1. 90

The member 2 is concaved centrally of its upper edge at 4 to provide space to accommodate the collar at the extremities of the turned-down portion thereof as a neater fit can be assured if the upper edges engage 95 the inner side of the fold at two points as at 5, than if the contact is of relatively great length. In the one form, however, the concaved or recessed edge is indispensable, as will hereinafter appear.

The member 2 in the preferred form is provided at points sufficiently spaced apart to underlie the turned-down ends of the collar, with vertical or equivalent slots or openings 6, a modification of such form being to 105 provide notches or openings 7 in the extremities of the member. In this case it is desirable that the member shall be of the shortest length practicable, for a reason herein-after mentioned.

The other part of the attachment of preferred type comprises a stiff member 8, for

100

110

spanning the space between the slots 6 or notches 7, terminating in hooks 9 for fitting through said slots or notches and interlocking the two members together, the part or member 9 constituting the element upon which the tie T is secured by a four-in-hand knot, as shown by Figure 1, it being necessary with this construction to secure the tie upon said member preliminary to securing the latter to member 2. When the members are interlocked prior to securing member 2 in place and when the latter is in place, the interlocking points of the members are hidden by the ends of the turned-down part of the collar, the tie being preferably wide enough where engaged with member 9, to completely hide the same from view, leaving in sight only that portion of member 2 which is below the member 9 and between the tie and the ends of the turned-down part of the collar. If the knot is snugly made, it hides the button, and if the member 2 corresponds in appearance with the collar, it would be noticeable only in the fact that the observer would miss the appearance of the overlapping collar tabs.

With the type described it is practicable and desirable to produce the conventional double knot. For one who prefers the "single" knot, the type of member 8 can be modified by providing it with the pendent tapering or triangular portion 10 as shown by Figure 5, this portion constituting a former or core around which the tie will be turned to produce a symmetrical knot, it being understood that the preceding description applies in all respects to the type of construction disclosed by Figures 6 and 7.

If it is desired to avoid exposing the head of the collar button, the member 2 may be equipped at its inner side with a resilient clip 11, for engagement with the button by snapping it thereon, the neck of the button forcing its way through the constructed mouth 12 of the clip. Any other suitable fastening might be employed within the principle of construction and mode of operation involved.

In Figures 9 and 10, a construction is shown which permits of the core or former and tie secured thereon, to be swung upwardly to facilitate the buttoning or securing of member 2 in position or its removal. In this case member 2 is equipped

with a wire or equivalent loop 13 and the core or former with a hinge loop 14 at its upper edge for detachable and pivotal engagement with the loop 13.

In Figure 11, the attachment is of a type for use particularly on soft collars (not shown) having loops or buttons for engagement respectively by the hooks 9^a or button holes (not shown) at the ends of the member. In this type the member 8 may be dispensed with and the tie secured directly to member 2, or the member 8 may be employed as above explained, that is may constitute a tie mount and be interlocked with member 2.

In Figure 12, the member 2 for fastening as described to the collar button by a button hole or clip or the like, is provided with a slot 11 adjacent the recessed edge of the collar, for the reception of the tie, which in this instance, is adapted to be tied around the portion of the member lying between the slot and said recessed edge. In this case, therefore, such recessed edge is indispensable to provide space for the tie under and adjacent the folds of the collar.

It will be apparent, of course, that it is possible to produce the attachment of spring wire in skeleton form, and it is to be understood that such construction is contemplated as it falls within the spirit and scope of the appended claims. As the method of removing the attachment without disturbing the tie is the reverse of the described method of securing it in place, a recapitulation or further brief description is believed to be unnecessary.

I claim:

1. A tie forming and holding device, comprising a member for securement to a turned-down collar against the band and under the turned-down portion thereof, and provided with spaced slots and with a core or former having hook ends engaging said slots.
2. In a tie forming and holding device, a member of resilient material, provided with a button-engaging feature and with a pair of slots equi-distant from said feature, and a tie core for detachable engagement with said slots.

In witness whereof I hereunto affix my signature.

HARRY SOLOMON.
